UNITED STATES PATENT OFFICE.

LAWRENCE NOLAN, OF NEW YORK, N. Y.

FOLDING HORSE.

No. 835,977.

Specification of Letters Patent.

Patented Nov. 13, 1906.

Application filed February 2, 1906. Serial No. 299,176.

To all whom it may concern:

Be it known that I, LAWRENCE NOLAN, a citizen of the United States, and a resident of New York, borough of Manhattan, in the 5 county of New York and State of New York, have invented a new and Improved Folding Horse, of which the following is a full, clear, and exact description.

This invention relates to horses or trestles 10 such as are used by artisans and workmen for supporting scaffolds.

The object of the invention is to produce a structure of this kind which is simple of construction and which may be folded into compact form when not in use or for transportation and which may be readily opened and set up when desired.

The invention consists in the construction and combination of parts to be more fully described hereinafter and particularly set forth in the claims.

Reference is to be had to the accompanying drawings, forming a part of this specification, in which similar characters of reference indicate corresponding parts in all the figures.

Figure 1 is a perspective showing the horse set up ready for use. Fig. 2 is a perspective showing the horse in its folded condition. 30 Fig. 3 is a cross-section taken in the plane of the line 3 3 of Fig. 1. This view illustrates the construction and arrangement of the main joint of the horse, together with a brace, which constitutes a feature of the invention. 35 Fig. 4 is an elevation in section, showing the upper portion of two of the legs of the device and means for connecting same. Fig. 5 is a perspective showing a partly-formed clip which is used to connect the bars shown in 40 Fig. 4. Fig. 6 is an end elevation showing the manner of attaching two of the other legs of the structure, and Fig. 7 is a perspective showing the joint and the brace referred to above.

45 Referring more particularly to the parts, 1 represents the body of the horse, which is formed of two A-frames. One of the A-frames is formed of two legs 4, which are attached together by means of a bolt 5, as indicated in Fig. 6. When the horse is set up, as 50 indicated in Fig. 1, the lower extremities of the legs 4 are spread apart, as shown.

55 Referring especially to Fig. 6, the connecting-bolt 5 may be a rivet, as shown. This bolt or rivet is preferably curved slightly, as shown, in the plane in which the legs may be

spread apart. Between the upper extremities of the legs 4 on the bolt 5 there is attached a connecting-bar 6. In order to make a secure connection between the bolt 5 60 and the legs 4, I provide clips 7, as indicated in Fig. 6, which are bent so as to engage the side edges of the legs and so as to form rudimentary sockets 8, receiving the same. The bodies of these clips are formed with bosses 9, 65 through which the bolt 5 passes, as indicated. A similar clip 10 is used for securing the bar 6 in position. From this arrangement it will be understood that the legs 4 may be readily spread apart, and the bar 6 may be rotated 70 upon the bolt 5 as a pivot. The legs of the other of the A-frames are connected together near their upper extremities by a joint 12, as shown in Fig. 4.

Referring especially to Fig. 4, I provide 75 bracket-plates 13, the upper portions whereof are formed into rudimentary sockets 14 to receive the upper extremities of the legs 11, as shown. The bodies of these plates are attached to the inner or adjacent faces of the 80 legs and are provided, preferably, with nibs 15, which penetrate the wood, so as to increase the security of the fastening, as will be readily understood. Near their lower extremities the bracket-plates 13 in their outer 85 faces are formed with oppositely-disposed recesses 16 of circular form, and these recesses receive and hold in position a tubular rest or sleeve 17. Through this tubular sleeve 17 and through the plates and the legs 90 a bolt or rivet 18 passes. The recesses 16 are formed most conveniently by forming an inwardly-projecting lip 19 on the face of the plate. In this way a joint is formed which while it operates to hold the legs securely together prevents undesirable rigidity. The 95 flexibility of this joint will be described more fully hereinafter. On the inner faces of the bracket-plates 13 spurs 20 are formed, which project toward each other, as indicated. 100 These spurs preferably taper slightly, as shown, and terminate in reduced tips 21 for a purpose which will appear more fully herein- 105 after. The sockets 14, referred to above, are preferably formed by providing the bracket- plates 13 with laterally-projecting wings 22, which are bent in substantial parallelism, so as to form a socket, as will be readily understood. The blank of which the bracket- 110 plates are formed is illustrated in Fig. 5. At the lower portion of each plate wings 23 are provided, similar to wings 22, which are

adapted to be bent in the same manner to form sockets at the lower portion of the bracket-plates. As indicated, each of the bracket-plates 13 is provided with an opening 24, through which the aforesaid rivet or bolt 18 passes.

The two **A**-frames are connected together at substantially their middle points by joints 25. The construction of these joints is shown most clearly in Fig. 3. Each joint comprises a clip 26, similar to the clips 7 described above, which are attached to the outer faces of the legs 4. Through this clip and through the legs 4 bolts or rivets 27 pass, which constitute pivots, enabling the two **A**-frames to rotate one upon the other. The clips 26 are connected at their sides by means of a brace 28, formed of two sections or links 29^a 29^b, which are pivoted together at 30 and pivoted to the clips 26 at the points 31 and 32. It will be understood that this brace 28 is adapted to be forced into its extended position, so as to maintain the legs of the two **A**-frames apart, as indicated in Fig. 1.

25 The construction of the joint 30 between the links 29^a 29^b, which constitute the brace, is shown most clearly in Fig. 7. Referring to this figure, it will be seen that one of the links (specified by the numeral 29^a) is offset laterally
30 beyond the pivot-bolt 30, which connects the links and is formed on its lower edge with a notch or recess 34. In this way the projecting extremity 35 of this link 29^a is thrown into the plane of the opposite link 29^b, and this link 29^b is formed with a corresponding notch 36, which lies opposite to the notch 34 aforesaid. With this arrangement the construction is such that when the links are forced substantially into the same straight
35 line the notches 34 and 36 engage each other, so as to lock the bars in an extended position. In this way it will be understood that the edges of the notches will not engage until the links have moved beyond their central position.
40 With this arrangement the links tend to move in the same direction in which they are forced in locking them, and hence they maintain themselves in position in a well-known manner.

50 At a suitable point on the bar 6 I provide the same with a plurality of openings 37. These openings are adapted to be engaged by the spurs 20 in the manner indicated in Fig. 1, while the bar 6 rests upon the sleeve 17, as
 55 shown.

55 shown.
In setting up the horse it will be understood that the **A**-frames are opened out upon their pivotal connections 25, while the brace 28 is allowed to remain folded—that is, the 60 legs of the two **A**-frames lie close together. When the bars are in this relation, the upper extremities of the legs 11 occupy substantially the relation shown in Fig. 4. The bar 6 will then be slipped into the space between

the spurs 20, so that the clips 21 will engage 65 one of the openings 37. In order to facilitate the passing of the bar 6 into the space between the spurs, it may be necessary to press the bodies of the legs 11 together near the joint 12, so that the spurs are forced slightly 70 apart. When the legs 11 and the spurs 20 resume their normal positions, the clips 21 will move inwardly sufficiently to engage the bar 6 and support the same. The brace 28 is then extended in the manner described above 75 by forcing its links into the same straight line. In extending the brace 28, as described, the legs 11 of one of the A-frames are forced apart below, while their upper extremities, carrying spurs 20, are forced together. In 80 this way the extremities of the spurs 20, near the reduced tips 21, press the sides of the bar 6 and lock the same against lateral movement.

In Fig. 2 the device is represented in its folded condition. When in this condition, the brace 28 is knocked down or folded and the lower ends of the legs 4 are rotated upwardly until they lie near the joint 12 in the space between the legs 11, and the bar 6 is folded around in an outward direction, so as to come between the legs 4, as illustrated. Attention is called to the fact that in opening up the device to set it up it may be opened in either direction, so that the brace 28 will be forced either downwardly or upwardly to lock the same. This feature is advantageous, as it does not necessitate special directions for setting up the horse.

By having several of the openings 37, as shown, the frame of the horse may be adjusted so as to support the bar 6 at different heights, as will be readily understood. When the brace 28 is extended as described, the feet of the A-frames are held at a substantial distance apart, so that a broad base for the structure is made, tending to prevent the same from being readily upset. It should be understood that two or more of these horses are used in the usual manner, boards or rails being laid upon the bar 6, so as to form a scaffold or platform in a well-known manner. In one aspect the entire structure below the bar 6 may be considered a folding frame.

Having thus described my invention, I claim as new and desire to secure by Letters Patent—

1. In a folding horse, in combination, a pair of legs, a joint connecting the same near their upper extremities, said legs having extensions projecting beyond said joint and having spurs, a second pair of legs pivoted respectively to said first legs, a bolt connecting said second pair of legs, said second pair of legs being adapted to swing through said first pair of legs, a bar pivotally carried by said bolt, and adapted to rest upon said joint, said bar having a plurality of openings on the cen- 120 125

tral line thereof, whereby said spurs may engage said openings with either edge thereof resting upon said connection.

2. In a folding horse, in combination, an **A**-frame comprising a pair of legs and a joint connecting the same near the upper extremities thereof, a second **A**-frame pivotedly attached on the inner side of said first **A**-frame, an extensible brace disposed between the legs of said first **A**-frame, a bar attached to the upper extremity of the said second **A**-frame and adapted to rest upon said joint, the upper extremities of said legs beyond said

joint having spurs for engaging said bar, said bar having a plurality of openings engaged by said spurs, the upper end of said second frame being adapted to swing through said first frame to come into a reversed position with said bar resting on said joint. 15

In testimony whereof I have signed my name to this specification in the presence of two subscribing witnesses.

LAWRENCE NOLAN.
